UNITED STATES PATENT OFFICE.

HENRY GEORGE, OF MANCHESTER, ENGLAND, ASSIGNOR TO EDWARD A. GODDING, OF PROVIDENCE, RHODE ISLAND.

TEMPORARY FILE OR BINDER.

SPECIFICATION forming part of Letters Patent No. 472,018, dated March 29, 1892.

Application filed November 4, 1891. Serial No. 410,831. (No model.) Patented in England September 23, 1891, No. 16,145.

To all whom it may concern:

Be it known that I, HENRY GEORGE, of Manchester, in the county of Lancaster, England, have invented certain new and useful Improvements in Temporary Files or Binders; and I hereby declare that the following is a full, clear, and exact description of the same, reference being had to the accompanying drawings, forming part of this specification.

10 This invention has reference to improvements in devices for filing or temporarily binding together letters, bills, &c.

The object of the invention is to produce a temporary binder which shall be simple in 15 construction, convenient in use, and effective in operation.

The invention consists in the peculiar features of construction and novel combination of parts, which will hereinafter be more fully 20 described, and pointed out in the claims.

Figure 1 represents an end view of the improved binding device and indicates the operation of the same. Fig. 2 represents a plan view of the binder to show the spring-catches.

25 Similar numbers of reference designate corresponding parts throughout.

In the drawings, 5 indicates a bed-plate, which may or may not be secured to a thin board of a size equal to that of the sheets of 30 letter-paper or of the bill-heads for which it is to be used. At the rear portion of this bed-plate and extending across the greater portion of the same is the bearing 6, which may be stamped up from the metal of the bed-

35 plate or may be formed of a separate piece and secured to the bed-plate. The tilting arms 7 7 are formed in part with and connected at their bases by a straight shaft extending through the bearing 6 at the upper portions.

40 These arms have the curved portions 8 8 and the pointed ends 9 9.

The spring-clips 10 10 are secured by the plates 11 11 to the base 5 and extend upward and rearward, partially surrounding the rear

45 portion of the tilting arms, the rear ends of these clips forming jaws 12, adapted to facilitate the entrance of the tilting arms between the shoulders of the clips. These clips may be secured in place to engage one of the

50 tilting arms, or the pair of clips may be separated by the width of the plate between the

tilting arms, and each of the pair engage a separate arm.

The vertical posts 13 13 are secured to the front portion of the plate or base 5 and may 55 be hollow, or they may be provided at their upper ends with sockets adapted to receive the pointed ends of the tilting arms. The upper ends of these posts 13 13 are also cut off at an angle to permit of their ready entrance 60 into the holes punched in the letter or bill heads, and a short distance below the upper ends these posts 13 13 are provided with transverse perforations 14 14, through which a tape or string may be passed when it is desired to 65 secure the contents of the binder together.

When in the closed position shown in solid lines in the drawings, the contents or any portion of the same can be readily moved from the posts 13 13 onto the tilting arms. When 70 the desired letter or bill is thus brought to view, a simple movement of the hand will throw the tilting arms backward, and the paper may then be removed from the file or binder, which is then closed by a slight forward pressure on the tilting arms, the spring-clips engaging with these arms and supporting 75 them in place.

When the entire contents are to be removed from the binder, a string or tape is usually 80 passed through the perforations 14 14 of both the posts 13 13, and after pushing back the tilting arms the contents are removed from the posts 13 13, the movement of the contents tending to thread the string or tape held in 85 the perforations 14 14 through the holes in the papers, which may now be secured together by tying the ends of the string or tape; or the operation may be reversed by first moving the contents of the binder upon the tilting arms and then inserting the string or tape through the perforations 14 14. The contents 90 may now be pushed back onto the posts 13 13, threading the string or tape through the perforations in the papers and tying the ends. 95

Having thus described my invention, I claim as new and desire to secure by Letters Patent—

1. In a temporary file or binder, the combination, with vertical posts secured on a bed-plate, of curved tilting arms having pointed ends adapted to register with the upper ends 100

of said vertical posts and connected by a shaft integral with said arms and working in a bearing secured to or formed in part with said bed-plate, and spring-clips adapted to support 5 said tilting arms, as described.

2. The combination, with the bed-plate 5, the bearing 6, secured thereto, and the tilting arms 7 7, having the curved portion 8 8 and pointed ends 9 9 and connected by a shaft extending through said bearing 6, of the posts 10 13, having the transverse perforations 14

14, and the spring-clips 10 10, having the jaws 12, secured to said plate 5 and adapted to engage one of said tilting arms and support the same, as and for the purpose described. 15

In witness whereof I have hereunto set my hand.

HY. GEORGE.
